UNITED STATES PATENT OFFICE.

EDWIN V. CALDWELL, OF HARPERSVILLE, ALABAMA.

HARROW.

SPECIFICATION forming part of Letters Patent No. 292,985, dated February 5, 1884.

Application filed May 5, 1883. (No model.)

To all whom it may concern:

Be it known that I, EDWIN V. CALDWELL, of Harpersville, in the county of Shelby and State of Alabama, have invented a new and useful Improvement in Adjustable Combination-Harrows, which improvement is fully set forth in the following specification and accompanying drawings, in which—

Figure 1 is a perspective view of the complete adjustable combination-harrow. Fig. 2 is a side view of the same. Fig. 3 represents the form of the harrow when used as a cultivator or as a double side harrow. Fig. 4 shows the harrow in form when used as a rake; Fig. 5, in the form of a single side harrow. Fig. 6 is an enlarged perspective view of the harrow-tooth.

The object of the present invention is to provide an adjustable combination-harrow capable of having all its parts detached or changed so as to assume a proper form and shape desirable for use as a harrow, cultivator, rake, pulverizer, cotton thinner or blocker, &c.; and it consists of a draft-beam having at its rear the two sets of transverse arms, with removable tooth-beams hinged to said arms, provided with teeth on the front beams forwardly inclined, and the teeth on the rear beams rearwardly inclined, and with an adjusting rod and clamp for regulating the same at any angle, all of which will now be set forth in detail.

In the accompanying drawings, A represents the draft-beam, and B B cross-arms at the rear end, located a short distance from each other. I prefer to have one of the cross-arms gained into the beam on the upper side, and a similar arm gained into the beam on the under side, and the two secured together and to the beam by a single bolt, C. The rear arms are preferably somewhat longer than the forward arms. Suitable handles, D, are secured to the rear end of the beam A, and project upwardly and backwardly, so as to be in convenient position to be grasped by the operator.

E E' represent the branching tooth-beams, which are hinged at their inner ends to the arms B B, as shown by the bolts at F. The outer ends of these beams are connected by the links G.

H represents an adjusting rod or bar running across from the tooth-beam on one side to the similar beam on the other side. This adjusting-bar is so arranged that the beams E E' may be projected out at nearly right angles to the draft-beam, or they may incline rearwardly, and when adjusted the central clamp, I, will hold the same in position.

Projecting upwardly from the clamp I are branching or radiating arms J, the upper ends of which are attached to the handles D for supporting the same.

K is a seat secured at its rear end to the post L, and supported at its forward end on the rods or legs M, which project upwardly from the beams E.

The teeth N are triangular in cross-section and bent centrally, as shown, the upper half, O, being vertical when in position, and the lower half, O', inclined either forwardly or rearwardly. The upper end is screw-threaded and provided with a shoulder, so that when the threaded end is placed through the beam and a nut put thereon the tooth can be firmly held to the beam. As will be observed in Figs. 1 and 2, the lower limbs, O', of the teeth on the two forward beams, E, incline forwardly, whereas the lower limbs of the teeth on the two rear beams, E', incline rearwardly. By their disposition the soil is more effectually pulverized than by having the teeth straight; and it is also obvious that the forward teeth will more easily penetrate the soil and stir up the same, while the inclined dragging shape of the rear teeth insures pulverization.

To convert the harrow into a cultivator, the rear beams, E', are removed, and the ends of the adjusting-rod H attached to the outer ends of the forward tooth-beams, E, as shown in Fig. 3. The beams E may be inclined at any angle to suit the requirements.

To provide a rake, the parts forming the adjustable bar H are separated and one of their ends secured to a bolt on the forward end of the beam, and the rear ends of the separated bars H secured to the forward beams, E. The beams E are secured to the forward arms B and projected out at right angles, the rear beams, E', being removed. The forward inclination of the teeth on the beam E causes them to act properly for raking purposes.

Fig. 4 represents this form to the best advantage. To convert it into a single side harrow or cultivator, only one of the forward beams, E, is used, and one of the sections of the adjusting-rod H. The latter being slotted or made in the form of a link permits the beam E to be thrown at any angle.

What I claim as new is—

The combination of the draft-beam A, having at the rear end the two sets of transverse arms B B, with the removable tooth-beams E E', hinged to said arms, provided with teeth

on the front beams forwardly inclined, and the teeth on the rear beams rearwardly inclined, and with the adjusting-rod H and clamp 15 I, substantially as herein set forth.

In testimony that I claim the foregoing I have hereunto set my hand, this 31st day of March, 1883, in the presence of witnesses.

EDWIN V. CALDWELL.
